UNITED STATES PATENT OFFICE.

SILAS S. BRADSHAW, OF BROOKLYN, NEW YORK, ASSIGNOR OF ONE-HALF
TO CHARLES LYONS, JR., OF NEW YORK, N. Y.

DESIGN FOR A PLATE FOR TRANSOM-LIGHTS.

SPECIFICATION forming part of Design No. 25,716, dated June 30, 1896.

Application filed April 6, 1896. Serial No. 586,455. Term of patent 7 years.

To all whom it may concern:

Be it known that I, SILAS S. BRADSHAW, a citizen of the United States, and a resident of Brooklyn, in the county of Kings and State 5 of New York, have invented and produced a new and original Design for Pivot-Plates for Transom-Lights, Reversible-Sash Windows, and other Like Structures, of which the following is a specification, reference being had 10 to the accompanying drawings.

Figure 1 is an elevation of the pivot-plates, showing my design. In this figure the two plates are represented as swiveled into the position where they lie one on top of the other. 15 Fig. 2 illustrates an elevation of the same, the two plates being swiveled on the central pivot, so that they lie at an angle to each other.

The leading feature of my design consists in making the pivot-plates of oblong form, and 20 having circular or rounded ends and sides composed of arcs of circles, the centers whereof are all upon the same longitudinal line.

In the drawings, A illustrates one of the pivot-plates; A', the other. B is the pivot

which connects them and upon which they 25 swivel, and C C' C² C³ are the screw-holes whereby the plates may be attached to respective parts of the structure with which they are used.

The design, as above stated, consists in giving 30 to the ends of each plate a circular outline, as shown at *aa*, and the portions between the ends are given a lateral outline in the form of arcs of circles, the centers whereof are in line with the centers of the circles composing the ends. The several arcs of the circles 35 composing the entire structure intersect each other, as shown.

The optical effect of my design is that of an oblong plate or structure having scalloped 40 sides and rounded or circular ends.

I claim—

The design for pivot-plates for transoms and like structures, herein shown and described.

SILAS S. BRADSHAW.
